UNITED STATES PATENT OFFICE

2,414,056

GRINDING APPARATUS

Lee L. Nieman, Chicago, Ill.

Application February 7, 1945, Serial No. 576,591

2 Claims. (Cl. 51—127)

1

This invention relates to improvements in grinding apparatus and is more particularly concerned with apparatus of this type adapted for use in finishing plaster cast plate dentures.

An object of the present invention resides in the provision of a pair of finishing wheels mounted, one behind the other, upon a rotatable shaft journaled within a suitable housing and in which said wheels are accessible for finishing plaster cast plate dentures from adjacent one face of the housing.

Another object of this invention is to provide an apparatus of this type embodying improved means for mounting and guiding plaster casts into position with one of the finishing wheels to provide casts of uniform predetermined contour.

A further object of this invention is to provide an apparatus of this type embodying improved means for collecting and confining particles of plaster removed from the plaster casts during the finishing operation.

This invention embodies other novel features, details of construction and arrangement of parts which are hereinafter set forth in the specification and claims and illustrated in the accompanying drawings wherein:

Fig. 1 is a front elevational view showing a grinding apparatus embodying features of this invention.

Fig. 2 is a fragmentary sectional view taken along the line 2—2 of Fig. 1 showing an air funnel which is adapted to be detachably connected to the front face of the housing to enclose one of the air inlet openings formed therein.

Fig. 3 is a sectional view taken along the line 3—3 of Fig. 1.

Fig. 4 is a fragmentary sectional view taken along the line 4—4 of Fig. 1 showing an improved turntable means for mounting and guiding a plaster cast into engagement with a grinding wheel.

Fig. 5 is a fragmentary sectional view taken along the line 5—5 of Fig. 4.

Referring now to the drawings for a better understanding of this invention, the grinding apparatus is shown as comprising a housing 6 formed with front wall 7, back wall 8, side walls 9 and 11, a bottom 12 and a top 13. An electric motor 14 is supported within the housing upon suitable brackets 16 and has its shaft detachably connected by means of a collar 17 to a shaft 18.

A relatively small diameter grinding or cutting wheel 19 is detachably mounted on the outer end of the shaft 18 by any suitable means (not

shown), and is adapted to project outwardly through an air inlet opening 21 provided in the front plate 7 of the housing. A relatively large diameter disc-shaped grinding wheel 22 is secured on the shaft 18 adjacent the inner side of the front wall 7. A suction air inlet opening 23 is formed in the front wall 7 of the housing adjacent the opening 21, and is shaped to permit insertion therethrough of a plaster cast 20 of a plate denture for grinding engagement with the side of the wheel 22.

A centrifugal blower 24 is also secured on the shaft 18 between the motor and the grinding wheel 22 for causing direct air to flow inwardly through the openings 21 and 23 and thence upwardly through an outlet passage 26 to the interior of a bag 27 or other dirt storage receptacle. A partition 28 is provided within the housing 6 between the motor 14 and the blower 24, and a partition 29 is provided between the grinding wheel 22 and the blower 24. The partitions 28 and 29 serve to form a blower compartment 31 within the housing. The partition 29 is preferably formed with an arcuate inwardly sloping face 32 for directing air and particles of plaster toward a central opening 33 leading to the blower compartment.

The bag 27 is formed of cloth or other suitable material to permit the escape of air therefrom and to retain any dirt or particles of plaster delivered thereto by the blower 24. The mouth of the bag is detachably connected to an annular boss defining the upper end of the outlet passage 26 by means of a clamping ring 34. A vacuum bag compartment 36 is provided in the housing, and a grilles opening 37 is formed on the back wall 8 to permit the passage of air from the bag compartment 36 to the exterior of the housing. A cover 38 is hingedly connected to the back wall 8 of the housing at 39 and is provided with a suitable lifting knob 41 on its forward edge for raising the cover to permit access to the bag 27.

A shelf 42 is supported on the front wall 7 of the housing by means of brackets 43 to receive three roller mounting bolts 44, 44a and 44b having sleeve rollers 46 journaled thereon. A turntable 47 is mounted on the shelf 42 and provided with a plurality of cam surfaces 48, 48a, 49 and 49a for operative engagement with sleeve rollers 46 to define the line of travel of the turntable. Abutment shoulders 51 and 51a are provided at the inner ends of the cam surfaces 48, 49 and 48a, 49a respectively. The turntable 47 is held against vertical displacement

by means of the flattened heads 52 provided on the bolts 44. A cover 53 is secured to the turntable 47 by means of screws 54, and is provided with a plurality of spaced apertures 56 to receive legs 57 provided on an adjustable back rest 58.

An air inlet funnel 61 is detachably connected to an annular flange 62 which is mounted on the front face of the housing and enclosing the air inlet opening 21. The funnel 61 is preferably formed in two parts comprising a cylindrical member 63 and an elbow member 64, said members being connected for relative rotational movement by means of annular coacting beads 66.

In the use of this apparatus for finishing a plaster cast denture 20, or the like, the cast is mounted upon the cover 53 with its back edge in engagement with the back rest 58. The turntable 47 is then turned to bring the peripheral wall of the plaster cast into grinding engagement with the side of the wheel 22, and it will be noted that the arcuate travel of the turntable 47 is controlled by means of the fixed pivots 44, 44a and 44b coacting with the several cam surfaces 48, 48a, 49, and 49a. The limit of arcuate travel of the turntable is controlled by the position of the stop-shoulders 51 and 51a. The cover 53 is adapted to accommodate casts of various lengths by adjusting the position of the back rest 58 with respect to the several apertures 56.

The front and back faces of the plaster cast 20 may be finished by holding same against the side of the wheel 22, and it will be observed that the opening 23 is shaped to conform to the outline of the cast.

The cutter 19 is employed for finishing the irregular interior shape of the plaster cast 20, and said cutter may be formed of metal with suitable cutting edges or may be in the form of a grinding wheel.

It is sometimes necessary to employ well known grinding and cutting tools of the type held manually and operated through a motor and flexible shaft for finishing artificial dentures. The air inlet funnel 61 is then employed for use to receive particles of material being removed from the denture, and it will be noted that the elbow section 64 may be rotated to the most convenient position for the operator during this finishing operation.

During the operation of this grinding and trimming apparatus, the blower 24 acts to draw streams of air through the openings 21 and 23

to direct entrained particles of material into the blower chamber 31 and thence through the outlet opening 26 into the dirt storage bag 27. It will be noted that the bag 27 may readily be removed from the housing 6 for the purpose of removal of dirt therefrom by merely raising the cover 38 and disconnecting the clamping band 34.

An electric lamp 66 is mounted on the front panel of the housing above the openings 21 and 23 and provided with a suitable reflector 67 for directing light downwardly upon the plaster cast during the finishing operations.

While this invention has been shown in but one form, it is obvious to those skilled in the art that it is not so limited but is susceptible of various changes and modifications without departing from the spirit and scope of the claimed invention.

I claim as my invention:

1. In an apparatus of the character described, a housing, said housing having a pair of air inlet openings formed in one wall thereof, a shaft journaled within said housing, a cutting wheel mounted on the end of said shaft to project through one of said air inlet openings, a disc-shaped grinding wheel mounted on said shaft adjacent the inner surface of the wall formed with the air inlet openings whereby material to be formed may be inserted through the other of said openings for engagement against said grinding wheel, a shelf provided on said housing, a turntable mounted on said shelf, cam surfaces formed on said turntable, and a plurality of fixed pivot pins secured to said shelf for engagement with said cam surfaces to direct said turntable along a predetermined line of movement.

2. In an apparatus of the character described, a housing, said housing having an air inlet opening formed in one wall thereof, a shaft journaled within said housing, a disc-shaped grinding wheel mounted on said shaft adjacent the inner surface of the wall formed with the air inlet opening whereby material to be formed may be inserted through said opening for engagement against said grinding wheel, a shelf provided on said housing, a turntable mounted on said shelf, cam surfaces formed on said turntable, and a plurality of fixed pivot pins secured to said shelf for engagement with said cam surfaces to direct said turntable along a predetermined line of movement.

LEE L. NIEMAN.
